Primary Examiner — David G Muller*Assistant Examiner* — Jamaal Rasheed(74) *Attorney, Agent, or Firm* — NSIP Law(57) **CLAIM**

We claim the ornamental design for an air purifier, as shown and described.

DESCRIPTION

FIG. 1 is a front perspective view of an air purifier showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view thereof;

FIG. 9 is a rear perspective view thereof;

FIG. 10 is an enlarged view of the encircled portion 10 in FIG. 1; and,

FIG. 11 is an enlarged view of the encircled portion 11 in FIG. 1.

The evenly-dashed broken lines in the figures depict portions of the air purifier which form no part of the claimed design.

The dot-dot-dash broken lines encircling portions of the claimed design that are illustrated in enlargements form no part of the claimed design.

1 Claim, 9 Drawing Sheets(56)
